UNITED STATES PATENT OFFICE.

EDGAR F. PRICE, OF NIAGARA FALLS, NEW YORK, ASSIGNOR TO UNION CARBIDE COMPANY, OF NIAGARA FALLS, NEW YORK, A CORPORATION OF VIRGINIA.

ELECTRIC HEATING.

SPECIFICATION forming part of Letters Patent No. 757,633, dated April 19, 1904.

Application filed April 5, 1902. Serial No. 101,502. (No model.)

To all whom it may concern:

Be it known that I, EDGAR F. PRICE, a citizen of the United States, residing at Niagara Falls, in the county of Niagara and State of New York, have invented certain new and useful Improvements in Electric Heating, of which the following is a specification.

This invention relates to the art of electrically heating materials, especially mixtures of a metallic compound and a reducing agent, and specifically a mixture of lime and carbon for the production of calcium carbide. The process contemplates the use as a heating means of a resistance-conductor placed in proximity to the materials to be heated. This conductor is heated by superposed electric currents passed through it, and the density of the current is thus increased along its path, thereby heating the conductor non-uniformly.

The process may be carried out by different forms of apparatus, two of which are shown in the accompanying drawings, in which—

Figure 1 is a vertical axial section of a stack-furnace, and Fig. 2 is a vertical longitudinal section of a horizontal or reverberatory furnace.

The furnace shown in Fig. 1 comprises a vertical stack 1 and frusto-conical bosh 2, of suitable refractory non-conducting material, such as fire-brick, and a crucible or hearth 3, of refractory conducting material, such as carbon. The hearth is provided with a tap-hole 4. A series of electrodes 5, arranged in a ring, depend into the upper part of the stack. One or more horizontal series of radial electrodes 6 7 may extend through the sides of the stack and bosh. The electrodes 5 6 7, which may be carbon rods, are connected to one terminal of a source of electric current, such as a direct-current or alternating-current dynamo, and the hearth 3 is connected to the other terminal. Within the furnace, and in contact with its walls is a tubular resistance-conductor 8, preferably of loose material, such as lumps of graphitized carbon or coke. The charge of material to be heated, 9, is arranged as a vertical column within and in contact with the resistance-conductor. It will

be seen that the resistance-conductor 8 by reason of the conical bosh 2 decreases in cross-sectional area toward the hearth, and its resistance thereby increases downwardly. When an electric current is passed between one of the upper electrodes and the hearth, the resistance-conductor is non-uniformly heated by reason of the gradually-increasing current density toward the hearth. The heat generated by the passage of the current and radiated to the material 9 thus increases downwardly. The current density in the lower part of the resistance-conductor is further increased by supplying additional current through the radial electrodes 6 and 7, the current flowing between the electrodes 6 and the hearth being superposed upon that passing between the upper electrodes 5 and the hearth and the current traversing the lower part of the resistance-conductor being supplemented by the amounts supplied by the lower electrodes 7. As the lower part of the column 9 of material to be heated—for example, a mixture of lime and carbon—is brought to a sufficient temperature the materials react to form calcium carbide, which may be allowed to accumulate as a pool in hearth 3 and drawn off from time to time through tap-hole 4 or allowed to run out continuously as produced. The column 9 thereupon gradually descends, and fresh material is fed in at the upper end. Such portions of the resistance-conductor as are carried down with the charge may also be replenished at the upper part of the furnace. The central column of material is heated not only by radiation and conduction from the surrounding resistance-conductor, but also by the waste gases passing up from the zones of reduction and fusion below. The resistance-conductor surrounding the column of material to be heated efficiently prevents loss of heat therefrom by radiation.

The furnace shown in Fig. 2 comprises end walls 10 11, floor 12, and roof 13, of refractory non-conducting material, such as fire-brick. A feed-hopper 14 and waste-gas pipe 21 pass through the roof. On the floor of the furnace lies a resistance-conductor 19, prefer-

ably of loose material, such as used in the stack-furnace previously described. The upper surface of this conductor slopes downwardly from a point beneath the hopper to the discharge end of the furnace. An electrode 15, such as a carbon rod, extends into the resistance-conductor at some point remote from the discharge end of the furnace and is connected to one terminal of a source of current. Another electrode, 17—for example, a carbon slab—is placed in contact with the resistance-conductor at the discharge end of the furnace and connected to the other terminal of the dynamo. A third electrode, 16, connected to electrode 15, may lead into an intermediate part of the resistance-conductor. The material to be heated, 20, is fed into the furnace through hopper 14 and distributed in a layer upon the resistance-conductor. An electric current is thereupon passed from electrodes 15, 16 to electrode 17, heating the conductor non-uniformly, the density of the current in the conductor increasing toward the discharge end of the furnace both by reason 25 of its diminishing cross-section and of the additional current supplied by the electrode 16. The same result may be effected by a resistance-conductor of uniform cross-section by supplying a sufficient amount of additional 30 current through electrode 16. In the furnace shown both expedients are employed to increase the current density toward the discharge-outlet. That portion of the charge 20—for example, lime and coke—near the discharge end of the furnace may soon be brought to a temperature sufficient to cause the materials to react to form carbide and the carbide to be brought into a molten condition, whereupon it will flow out from the furnace 35 through tap-hole 18. The charge 20 is then moved downward upon the conductor and fresh material introduced. If desired, the tap-hole may be temporarily closed by a plug of refractory material, and the carbide drawn off 40 intermittently.

1. claim—

1. The process of heating materials, which consists in placing the material in proximity to a stable resistance-conductor, and passing 50 superposed electric currents through said conductor, thereby increasing the current density along the path of the current, through a portion of the conductor in proximity to said material, as set forth.

2. The process of heating materials, which consists in placing the material in proximity to a resistance-conductor of loose, broken or granular material, and passing superposed electric currents through said conductor, thereby increasing the current density along the path of the current, through a portion of the conductor in proximity to said material, as set forth.

3. The process of reducing a compound, 55 which consists in placing a mixture of the com-

ound and a reducing agent in proximity to a stable resistance-conductor, and passing superposed electric currents through said conductor, thereby increasing the current density along the path of the current, through a portion of the conductor in proximity to said material to a point where the heat generated by the resistance of the conductor effects reduction, as set forth.

4. The process of reducing a compound, 75 which consists in placing a mixture of the compound and a reducing agent in proximity to a resistance-conductor of loose, broken, or granular material, and passing superposed electric currents through said conductor, thereby increasing the current density along the path of the current through a portion of the conductor in proximity to said material to a point where the heat generated by the resistance of the conductor effects reduction, as 85 set forth.

5. The process of producing carbids, which consists in placing carbid-forming materials in proximity to a stable resistance-conductor, and passing superposed electric currents 90 through said conductor, thereby increasing the current density along the path of the current through a portion of the conductor in proximity to said material to a point where the heat generated by the resistance of the conductor causes the materials to react to form carbid, as set forth.

6. The process of producing carbids, which consists in placing carbid-forming materials in proximity to a resistance-conductor of 100 loose, broken or granular material, and passing superposed electric currents through said conductor, thereby increasing the current density along the path of the current through a portion of the conductor in proximity to 105 said material to a point where the heat generated by the resistance of the conductor causes the materials to react to form carbid, as set forth.

7. The process of producing carbids, which 110 consists, in placing carbid-forming materials in proximity to a stable resistance-conductor, and passing superposed electric currents through said conductor, thereby increasing the current density along the path of the current through a portion of the conductor in proximity to 115 said material to a point where the heat generated by the resistance of the conductor causes the materials to react to form carbid, and the carbid to be brought into a 120 molten condition, as set forth.

8. The process of producing carbids, which 125 consists, in placing carbid-forming materials in proximity to a resistance-conductor of loose, broken or granular material, and passing superposed electric currents through said conductor, thereby increasing the current density along the path of the current through a portion of the conductor in proximity to said material to a point where the heat generated by 130

the resistance of the conductor causes the materials to react to form carbid, and the carbid to be brought into a molten condition, as set forth.

5 9. The process of producing carbids, which consists in placing carbid-forming materials in proximity to a stable resistance-conductor, passing superposed electric currents through said conductor, thereby increasing the current 10 density along the path of the current through a portion of the conductor in proximity to said material to a point where the heat generated by the resistance of the conductor causes the materials to react to form carbid, and the 15 carbid to be brought into a molten condition, and tapping off said molten carbid and supplying fresh material as required, as set forth.

10 10. The process of producing carbids, which consists in placing carbid-forming materials 20 in proximity to a resistance-conductor of loose, broken or granular material, passing superposed electric currents through said conductor, thereby increasing the current density along the path of the current through a portion 25 of the conductor in proximity to said material to a point where the heat generated by the resistance of the conductor causes the materials to react to form carbid, and the carbid to be brought into a molten condition, and 30 tapping off said molten carbid and supplying fresh material as required, as set forth.

11. The process of heating materials, which consists in placing the material in proximity to a stable resistance-conductor, and passing 35 superposed electric currents through said conductor, thereby increasing the current density in a portion of said conductor in proximity to said material and heating it ununiformly, as set forth.

40 12. The process of heating materials, which consists in placing the material in proximity to a resistance-conductor, of loose, broken or granular material, and passing superposed electric currents through said conductor, 45 thereby increasing the current density in a portion of said conductor in proximity to said material and heating it ununiformly, as set forth.

13. The process of reducing a compound, 50 which consists in placing a mixture of the compound and a reducing agent in proximity to a stable resistance-conductor, and passing superposed electric currents through said conductor, thereby increasing the current density 55 in a portion of said conductor in proximity to said material to a point where the heat generated by the resistance of the conductor effects reduction, as set forth.

14. The process of reducing a compound, 60 which consists in placing a mixture of the compound and a reducing agent in proximity

to a resistance-conductor, of loose, broken or granular material, and passing superposed electric currents through said conductor, thereby increasing the current density in a portion of said conductor in proximity to said material to a point where the heat generated by the resistance of the conductor effects reduction, as set forth.

15. The process of producing carbids, which 70 consists in placing carbid-forming materials in proximity to a stable resistance-conductor, and passing superposed electric currents through said conductor, thereby increasing the current density in a portion of said conductor in proximity to said material to a point where the heat generated by the resistance of the conductor causes the materials to react to form carbid, as set forth.

16. The process of producing carbids, which 80 consists in placing carbid-forming materials in proximity to a resistance-conductor, of loose, broken or granular material, and passing superposed electric currents through said conductor, thereby increasing the current 85 density in a portion of said conductor in proximity to said material to a point where the heat generated by the resistance of the conductor causes the materials to react to form carbid, as set forth.

17. The process of producing carbids, which consists in placing carbid-forming materials in proximity to a stable resistance-conductor, passing superposed electric currents through said conductor, thereby increasing the current 95 density in a portion of said conductor in proximity to said material to a point where the heat generated by the resistance of the conductor causes the materials to react to form carbid, and the carbid to be brought into 100 a molten condition, and tapping off said molten carbid and supplying fresh material, as required, as set forth.

18. The process of producing carbids, which consists in placing carbid-forming materials 105 in proximity to a resistance-conductor, of loose, broken or granular material, passing superposed electric currents through said conductor, thereby increasing the current density in a portion of said conductor in proximity to said material to a point where the heat generated by the resistance of the conductor causes the materials to react to form carbid, and the carbid to be brought into a molten condition, and tapping off said molten carbid 115 and supplying fresh material as required, as set forth.
